UNITED STATES PATENT OFFICE.

JOHN WALKER, OF TORONTO, ONTARIO, CANADA.

CORNER-BRACKET FOR BED-FRAMES.

1,334,639.

Specification of Letters Patent. Patented Mar. 23, 1920.

Application filed March 27, 1919. Serial No. 285,448.

To all whom it may concern:

Be it known that I, JOHN WALKER, of the city of Toronto, in the county of York, in the Province of Ontario, Canada, have invented certain new and useful Improvements in Corner-Brackets for Bed-Frames, of which the following is the specification.

My invention relates to improvements in corner brackets for bed frames and the object of the invention is to devise a corner bracket which cannot work loose, in which all adjustments are made at the outside of the bracket where they can be readily gotten at, in which there are no dove-tail portions liable to fracture, which is so formed as to securely hold the angle side bar of the bed either in the normal or inverted position so that it will be impossible to have side play or work loose and in which the side bars of the bed frame may be connected thereto without the use of special tools and it consists essentially of the following arrangement and construction of parts as herein-after more particularly explained.

Figure 1, is a perspective view of my corner bracket showing it attached to a portion of a bed post.

Fig. 2, is a vertical section through Fig. 1.

Figs. 3 and 4, are perspective details of the divided portions of the locking block employed in connection with my bracket.

In the drawings like characters of reference indicate corresponding parts in the various figures.

1 indicates the bed post which is tubular. 2 indicates an inserted piece segmental in form and adapted to fit within the tubular post 1 on that side to which the corner bracket is to be attached. The inserted piece 2 is provided with orifices 2^x and 2° in proximity to each end thereof. 3 indicates my corner bracket which comprises a vertically disposed portion 3^x having its interior face concaved at 3° longitudinally so as to fit the interior face of the bed post when set longitudinally thereof. The central portion of the interior concaved surface 3° is recessed at 3¹ in order that the bracket may grip the bed post securely and have a biting connection thereto at each end. 3² and 3³ indicate orifices extending through the portion 3^x in proximity to each end thereof and in alignment with the orifices 2^x and 2°. 4 indicates rivets which extend through the alined orifices 2^x and 3² and 2° and 3³ thereby securely

and permanently fastening the bracket portion 3^x to the bed post.

3⁴ indicates a rectangular socket, which extends horizontally from the portion 3^x. 3⁵ indicates an orifice formed in the portion 3^x and in the base of the socket 3⁴. 1° indicates an orifice formed in the bed post in alinement with the orifice 3⁵. 2° indicates an orifice formed in the inserted piece 2 in alinement with the orifices 1° and 3⁵. 4^x indicates a bolt, which extends through the orifices 2°, 1° and 3⁵ and through the rectangular socket 3⁴ so as to protrude from the end thereof.

5 indicates a clamping or securing block which is divided diagonally into two portions 5^x and 5° as will be clearly seen in full lines in Figs. 3 and 4 and by dotted lines in Fig. 1. The plane of division not only inclines from front to rear of the block but also inclines from side to side thereby tending to force the portions 5^x and 5° of the block laterally one of the other when forced together in the inserted position within the socket. The block 5 is of such a size as to leave a space between two sides of the block and the opposing walls of the socket 3⁴ to permit of the insertion of the side angle bar 6 of the bed frame.

The outer end of the bolt 4^x is threaded and provided with a wing nut 7. 5¹ and 5² indicate orifices extending longitudinally through the block portions 5^x and 5° in alinement one with the other and through which the bolt 4 extends, the orifices 5¹ and 5² being sufficiently large to allow the free movement of the block in the direction required.

In securing the side bar 6 of the bed frame in position within the corner bracket all that it is necessary to do is to loosen the wing nut 7 upon the bolt 4^x so as to allow of free movement of the block portions 5^x and 5°. The end of the bar 6 is then inserted in the position clearly shown in Fig. 1 and the wing nut 7 tightened thereby drawing the block portions 5^x and 5° together so as to move them outwardly one from the other in an expanding direction toward the interior face of the socket 3⁴ thereby clamping both the horizontal and vertical flange of the bar against the corresponding wall of the socket.

In some cases it is desired to insert the side bars 6 of the bed frame in an inverted

position with the flange which is shown vertically in Fig. 1 extending horizontally supported upon the lower wall of the socket 3⁴ and the horizontal flange shown in Fig. 5 1 vertically against the outer wall of the socket 3⁴. In order to do this with my construction all that it is necessary to do is to loosen the wing nut 7 so as to free the block portions 5^x and 5°, withdraw the 10 bar 6, place it in the inverted position, move the block portions 5^x and 5° upward and reinsert the bar 6 in the inverted position. The wing nut 7 is then retightened.

In order to carry the cross bar of the bed frame I have provided the socket with an angle piece 8 extending outwardly therefrom and formed integral therewith, the vertical flange 8^x thereof being secured by rivets 8° to the vertical flange 9° of the 20 cross bar 9.

From this description it will be seen that I have devised a corner bracket which cannot work loose for the reason that the portions 5^x and 5° of the block 5 are wedged 25 together in the socket 3⁴ clamping the side bar firmly in place, in which the connection of the corner bracket to the bed post is provided without the employment of nuts located in the interior of the tubular bed 30 post. It is very common for these interior nuts to work loose and if such should be the case it is impossible for an ordinary person to retighten the bracket as it then requires a special tool which is inserted longitudinally through the bed post to grip 35 the nut. In my construction of bed corner bracket any manipulation which takes place is done exteriorly of the bed post and,

therefore, can be performed by any ordinary person who is the user of the bed. 40 It has also been found in ordinary constructions of corner brackets employing dove-tail joints that the dove-tails are liable to fracture at the neck or weakest part of the dove-tail. By my construction this defect is eliminated. Also any holes in the side bars of the bed frame are dispensed with which are usually necessary for riveting and which tend to weaken the side bar at a point where the greatest strength is 45 necessary. By my construction also the side bar is securely and positively clamped in position and can be readily held either in the normal or in the inverted position as desired. At the same time I have provided 50 a cheap and easily manufactured form of bed bracket.

What I claim as my invention is.

The combination with the bed post, of a bolt secured within the bed post and extending through the wall thereof, a bracket having orifices through which the bolt passes, a side bar receiving socket carried by the bracket, opposing wedge blocks fitting within the socket and having alined orifices 65 greater than the diameter of the bolt and through which the bolt loosely passes, the broad end of the inner wedge block bearing against the base of the socket, and a nut threaded upon the bolt and bearing against 70 the outer end of the opposing block.

JOHN WALKER.
